POST HOLE DIGGER

John W. Houston, Tama, Iowa

Application March 10, 1942, Serial No. 434,117

10 Claims. (Cl. 255—19)

This invention relates to a post hole digger, and it is a particular object of the invention to provide a device of this kind designed to be employed in connection with a tractor having a take-off shaft and wherein the digger is operated from said take-off shaft.

The invention also has for an object to provide a digger of this kind to be employed in connection with a tractor and wherein the mounting and operation of the apparatus is such to allow for proper spotting of the auger of the digger without requiring exact spotting of the tractor.

Another object of the invention is to provide a digger of this kind which can be employed for digging post holes or similar holes, and whereby such a hole may be produced on any lateral incline within a range of approximately 20°, or on a forward and rearward incline within a range of 30°.

A still further object of the invention is to provide a digger of this kind including a digging element or auger which can be readily adjusted to all inclines up to 20° and 30° and effectively locked in desired selected adjustment and wherein mounting of the digging element or auger is such as to center itself by gravity when the locking means is released.

A still further object of the invention is to provide an apparatus of this kind wherein the digging element constitutes an auger together with the use of a spreader for removing dirt from around the top of the hole being bored so that dirt will not fall into the hole when the auger is removed.

The invention consists in the details of construction and in the combination and arrangement of the several parts of my improved post hole digger whereby certain important advantages are attained, as will be hereinafter more fully set forth.

In order that my invention may be the better understood, I will now proceed to describe the same with reference to the accompanying drawings, wherein:

Figure 1 is a view in rear elevation of a post hole digger constructed in accordance with an embodiment of my invention and in applied position, the associated tractor being illustrated in fragment;

Figure 2 is a view in top plan of the structure as illustrated in Figure 1, with certain of the parts omitted;

Figure 3 is a detailed sectional view taken substantially on the line 3—3 of Figure 2, looking in the direction of the arrows;

Figure 4 is a detailed sectional view taken substantially on the line 4—4 of Figure 2, looking in the direction of the arrows;

Figure 5 is a detailed sectional view taken substantially on the line 5—5 of Figure 2, looking in the direction of the arrows;

Figure 6 is a detailed sectional view taken substantially on the line 6—6 of Figure 4, looking in the direction of the arrows;

10 Figure 7 is a detailed sectional view taken substantially on the line 7—7 of Figure 4, looking in the direction of the arrows;

Figure 8 is a fragmentary side elevational view at the rear portion of the apparatus, with parts in section;

Figure 9 is a detailed view, partly in elevation and partly in section, illustrating the means as herein embodied for coupling the digger to the tractor;

20 Figure 10 is a detailed view, partly in section and partly in elevation, illustrating one of the clutches as herein employed; and

Figure 11 is a fragmentary view in top plan illustrating the operative connection between the boom and housing for the auger, as herein comprised.

As disclosed in the accompanying drawings, 1 denotes a rigid draw member disposed transversely of the tractor T at the rear thereof and securely anchored thereto, as at 2. The tractor T may be of any type preferred but including, of course, a suitably positioned power take-off shaft. As this power take-off shaft is conventional and forms no part of the present invention an illustration and description thereof is believed to be unnecessary.

Anchored, as at 3, to the central portion of the member 1 is an elongated plate 4 provided at its extremities with the upstanding arms or posts 5. These arms or posts 5 are of desired length and have their upper end portions pivotally connected, as at 6, with the forward end portions of the side sills 7 comprised in the supporting frame or structure. These sills 7 are of required length and spaced apart a desired distance, and as herein disclosed are also substantially in parallelism and are maintained in desired assembly by the suitably positioned intermediate cross members 8 rigidly secured thereto.

50 The cross member 8 at the forward end portion of the device has overlying the front face thereof a plate 9 provided in an end portion with a plurality of longitudinally disposed and suitably spaced slots 10. Disposed through each of these slots 10 is a bolt 11 which is also directed

through the associated member 8. Threading upon each of these bolts 11 and coacting with the plate 9 are the holding or clamping nuts 12. The bolts 11 and nuts 12, in coaction with the slots 10, provide means whereby the plate 9 may be adjusted as desired within a limited range along the member 8. Overlying the plate 9 is a second plate 14 provided with a plurality of transversely disposed and longitudinally spaced slots 15 through which pass the bolts 16 and also directed through the adjacent portion of the plate 9. Threading upon these bolts 16 and coacting with the plate 14 are the conventional holding or clamping nuts 17. As is particularly illustrated in Figure 3, the slots 15 are at right angles to the slots 10 and said slots 15 allow vertical adjustment of the plate 14 within certain limits independently of the plate 9, although it is to be pointed out that upon longitudinal adjustment of the plate 9 the plate 14 is correspondingly shifted therewith.

The central portion of the plate 14 has formed therewith an outstanding arm 18 provided at its outer extremity with an upstanding bearing 19 to provide a mounting for a short drive shaft 20. This shaft 20 is adapted to be coupled, as generally indicated at 21, with the power take-off shaft of the tractor T with which the apparatus or device is employed. As the means for connecting this shaft 20 with the take-off shaft of the tractor in its detail forms no particular part of the invention and is dependent upon the type or style of the tractor, a detailed description or illustration of this connection is not deemed necessary.

The shaft 20 extends inwardly of the bearing 19 and fixed to said shaft 20 for rotation therewith is a sprocket wheel 22. This sprocket wheel 22 is interposed between the bearing 19 and the plate 14, said arm 18 being of a length sufficient to permit such assembly.

Operatively engaged with the sprocket wheel 22 is an endless sprocket chain 23 which is also disposed around a sprocket wheel 24 freely mounted on a sleeve or hub 25 keyed, as at 26, or otherwise fixed for rotation with a shaft 27. This shaft 27 is disposed lengthwise of the device or apparatus or substantially parallel with the sills 1 and positioned at a point substantially midway between the sills 1. This shaft 27 is of a length to extend a major distance along the apparatus and is rotatably supported by the bearings 28 mounted upon the cross members 8.

The adjustment of the plates 9 and 14 permit required adjustment of the shaft 20 to assure the same being brought into effective position with respect to the take-off shaft of the tractor or to tighten the sprocket chain 23 as may be required.

The hub or sleeve 25, as particularly illustrated in Figure 10, is provided with a surrounding flange 29 one face of which having contact with the inner face of the web 30 of the sprocket wheel 24. Contacting with the opposite face of the flange 29 is an annular floating disk 31. The web 30 and the disk 31 are normally maintained in required frictional contact with the opposite faces of the flange 29 by the expandable members 32 of requisite tension and herein disclosed as coil springs interposed between the disk 31 and the heads or enlargements 33 threading upon the outer end portions of the elongated shanks 34 fixed to and carried by the web 30 and freely disposed through the annular disk 31. This assembly provides a clutch which normally allows

rotation of the shaft 27 with the shaft 20, but which clutch will slip and become ineffective upon abnormal load or resistance being imposed upon the shaft 27. It is to be stated at this time that any other form of automatic or overload clutch may be employed in lieu of the type of clutch as herein embodied and as particularly illustrated in Figure 10 of the drawings.

The cross member 8 at the rear end of the apparatus has operatively connected therewith, as at 35, a caster wheel 36 to provide support for said rear portion of the apparatus and, as is illustrated in Figure 2, this caster wheel 36 is positioned substantially midway between the sills 1. Welded or otherwise secured to the top face of this rear member 8 is a bearing 37 which provides a mounting for the lower end portion of an upwardly and laterally inclined shaft 38. This shaft 38 is disposed on a predetermined angle with respect to the horizontal and has fixed to its lower end portion a beveled gear 39 which meshes with a beveled gear 40 fixed to the adjacent or rear end portion of the shaft 20. This shaft 38 intermediate its length is further supported by the bearings 41 carried by the upstanding bracket arms 42 suitably secured to the sills 1 at the side of the apparatus beyond which the shaft 38 extends.

The upper or outer end portion of the shaft 38 has universal connection, as at 43, with an end portion of a shaft section 44 which telescopically engages within a second shaft section 45 of material length. The shaft 44 is angular in cross-section and the associated bore of the shaft 45 is of corresponding cross-section so that the two shafts 44 and 45 will rotate in unison, yet be free to have endwise movement one with respect to the other. The shaft 45 at its outer end has universal connection, as at 46, with a shaft section 47 which extends within a housing 48 and has conventional driving connection with a shaft 49 depending from the housing 48. As the driving connection between the shaft 47 and the shaft 49 is through a conventional assembly of gears, it is not believed a detailed description or illustration is required.

Suitably coupled, as at 50, to the shaft 49 is an auger 51 of desired dimensions. The coupling 50 may be as preferred but of a type permitting ready removal or application of the auger or to allow for the use of an extension shaft for the auger when it is desired to dig a hole of material depth.

The lower end portion of the auger 51 is provided with the outstanding and surrounding auger knife 52 having diametrically opposed and depending cutting knives 53 for severing or removing roots or kindred obstructions before reaching the central cutting edge 54 of the knife 52. This cutting edge 54 is downwardly sloped and serves to initially loosen the soil at the center of the hole to be dug and thereby facilitate the downward feeding of the auger 51. A series of cutting edges 54 may be employed. The cone point b of the auger 51 immediately below the knife 52, as illustrated, has its periphery smooth and unobstructed as it is not necessary that such periphery be threaded although this well known expedient may be employed if preferred.

The upper portion of the auger 51 is provided with the radially aligned outstanding arms 55 fixed for rotation therewith and carrying the vertically disposed flat blades 56 having their under edges a substantially straight from end to end and aligned with each other and substantially

perpendicular with respect to the axis of the auger 51. These blades 58 serve to effectively spread the dirt removed by the auger during the digging or drilling of a hole so that such dirt will not fall into the hole when the auger 51 is removed.

Freely mounted on and surrounding the outer end portion of the shaft 45 is a sleeve 57. Formed with this sleeve 57 at opposite sides thereof are the arms 58 which extend a desired distance beyond the outer end of the sleeve 57. The extended extremities of the arms 58 are flattened, as at 59, and hingedly connected, as at 60, to said portions 59 are the extended end portions of the elongated bars or rods 61 at opposite sides of the housing 48 and rigidly carried thereby. These bars or rods 61 provide effective means to keep the shafts 45 and 47 in what may be termed a straight relative position in all positions of the auger.

Rigidly secured, as at 62, in any manner preferred is the lower end portion of an upstanding post or column 63 of desired length and angular in cross-section. Slidably and snugly mounted upon this post or column 63 is a sleeve 64 with which is pivotally connected, as at 65, the arms 66 at opposite sides of said sleeve 64. These arms 66 extend inwardly from the sleeve 64 and carry a frame 67 in which is rotatably mounted a pulley 68. Suitably anchored, as at 69, to the upper portion of the frame 67 is an end portion of an elongated rod 70 having its outer extremity formed to provide a depending extension arm 71 disposed on a predetermined angle. This extension arm 71 is rotatably received within a bearing 72 carried by the upper extremity of an elongated boom 73 disposed on an angle of approximately 45° outwardly and laterally with respect to the apparatus or device. The extension arm 71, as herein disclosed, is provided with a surrounding collar 74 contacting with the outer end of the bearing 72 and with which engages a holding bracket 75 rigidly anchored, as at 76, to the bearing 72.

The lower extremity of the boom 73 is snugly received between a pair of upstanding posts 77 and welded or otherwise rigidly secured thereto. These posts 77 are rigidly supported by the inner end portions of a pair of parallel side beams 78 carried by a turntable 79. This turntable 79 is mounted upon a carriage 80 having movement lengthwise along the tracks 81 mounted upon the spaced parallel sills 82 welded or otherwise rigidly secured to a side sill 7. The outer end portions of the sills 82 are connected by a cross member 83 and operatively engaged, as at 84, with the central portion of this member 83 is a second caster wheel 85 to provide further support for the apparatus or device. The outer end portion of each of the beams 78 has secured thereto, as at 86, an end portion of a brace member 87, the opposite end portion of which being anchored, as at 88, to the central portion of the boom 73. Each of the upstanding posts 77 has associated with the lower portion thereof the brace member 87 interposed between the posts 77 and the adjacent side beam 78.

The pivotal connection 65 for the post or column 63 allows the same, together with the housing 48 and auger 51, to be swung laterally or sidewise in a general direction lengthwise of the shaft sections 44 and 45 to a selected incline at either side of the vertical within a range of 20° at either side of the vertical. The mounting of the rod 70, or more particularly the extension arm 71 there-

of, allows the post or column 63 and the parts associated therewith to swing forwardly and rearwardly of the vertical, or in a general direction substantially at right angles to the shaft sections 44 and 45. This swinging adjustment of the post or column 63 is readily permitted due to the relative endwise movement of the telescoping shafts 44 and 45. The post or column 63 as herein disclosed is caused to swing laterally or sidewise as desired through the medium of an elongated rod 89 operatively connected, as at 90, with the post or column 63 above its pivotal connection 65, and with a hand lever 91 mounted, as at 92, upon the boom 73 for swinging movement in a direction lengthwise of said boom. This lever 91 carries a conventional latch mechanism 93 for coaction with a rack 94 mounted upon the boom 73 whereby the post or column 63 may be effectively locked in desired lateral or sidewise swinging adjustment.

Disposed over the pulley 68 and connected at one end, as at 95, with the housing 48 is an end portion of a flexible member 96. The opposite end portion of this member 96 extends downwardly and under a pulley 97 rotatably supported by and between the upstanding posts 77. This member 96 extends from the pulley 97 to and winds upon a drum 98 fixed to rotate with a shaft 99 rotatably supported above the shaft 27 and to the outer side thereof by the upstanding frames 100 rigidly mounted upon adjacent cross members 8. Each of these frames 100, as herein disclosed, is V-shape in form with its apex upwardly disposed, and the shaft 99 is carried by the outer leg of such frame. The shaft 99 has fixed thereon a conventional clutch member 101 with which coacts a second clutch member 102 keyed to a shaft 103 but free for sliding movement therewith. This shaft 103, as herein disclosed, is in alignment with the shaft 99 and has a reduced end portion 104 which telescopes within the adjacent end portion of the shaft 99 whereby said shaft 99 provides a support for the shaft 103. The opposite end portion 45 of the shaft 103 is rotatably supported by a bearing 105 carried by the outer leg of an additional upstanding frame 106 suitably mounted upon a properly positioned cross member 8. This frame 106 is also V-shape in form with its apex 50 upwardly directed. The shaft 103 has fixed thereto for rotation therewith a gear wheel 107 which constantly meshes with a pinion 108 fixed to and rotating with the shaft 27.

The sliding clutch member 102 is provided with 55 an outstanding hub 109 having therearound a peripheral groove 110 in which engages from below a lever 111. This lever 111 has its lower extremity pivotally connected, as at 112, with a suitably formed bracket 113 fixed to and extending upwardly from the adjacent sill 7. The upper portion of the lever 111 overlies and has close contact with a holding arm 114 suitably supported by the inner leg of the frame 106, or otherwise as may be preferred. The upper or outer face of this arm 114 is provided thereacross with the suitably spaced recesses 115 in which the lever 111 is selectively engaged to hold the clutch member 109 in either its clutched position or its declutched position.

When the clutch members 101 and 102 are in engagement and, of course, the shaft 103 in rotation, the shaft 29 is rotated in a direction to wind the flexible member 96 upon the drum 98 to lift the auger 51 above the ground surface 75 when desired and, of course, to extract the auger

from within a hole. The auger 51 is held in desired rested position upon tightening a brake band 116 disposed around a brake pulley 117 provided at one end portion of the drum 98. An intermediate portion of this band 116 is 5 connected in a well-known manner, as at 118, with the upper end portion of an arm 119 carried by and extending upwardly from the adjacent side sill 7. The extremities of this brake band 116 are connected in the usual manner, as at 120 (Figure 1) with an end portion of a floating operating lever 121. The outer or free end portion of this lever 121 has anchored thereto, as at 122, an end portion of an elongated flexible member 123 disclosed in the accompanying drawings as a chain. This member or chain 123 passes around a guide pulley 124 coupled, as at 125, to the upper extremity of an upstanding post 126 rigidly anchored to the adjacent sill 7.

The member or chain 123 leads from the pulley 124 to a hand lever 127 and is operatively connected therewith, as at 128. The lower portion of this lever 127 is pivotally connected, as at 129, with an upstanding post 130 carried by the adjacent sill 7, and this post is provided with a rack 131 with which coacts in a well-known manner the latch mechanism 132 carried by the lever 127. By proper adjustment of the lever 127 the drum 78 may be locked to hold the auger 51 in desired raised position, or said lever 127 can be so adjusted as to control and regulate the downward movement of the auger 51, and particularly when said auger is being initially set for digging or drilling a hole.

As particularly illustrated in Figure 8 of the drawings, the inner portion of the shaft 99 and, of course, the associated portion of the shaft 103 are further supported by an upstanding bearing frame 133 mounted on one of the cross members 8.

The carriage 80, as herein disclosed, is elongated and is provided at its extremities and at opposite sides thereof with the flanged wheels 134 which have direct riding or rolling contact with the tracks 81 hereinbefore referred to. The side marginal portions of the table 80 are defined by the depending flanges 135 which overlie and have close contact with the upstanding flanges 136 extending along the side marginal portions of a bed plate 137 which is rigidly anchored, as by welding, to the adjacent sill 7. The flanges 135 of the carriage 80 are outwardly of the flanges 136 of the bed plate 137 and depending from the flanges 135 and rigidly secured thereto are the arms 138. These arms 138 are positioned at the central part of the flanges 135 and are of a length to extend a distance below the bed plate 137 sufficient to allow the mounting therebetween of a roller 139. This roller 139 has direct contact from below with said bed plate 137. This coaction between the roller 139 and the bed plate 137 assures the effective maintenance of the carriage on its tracks 81 and further to maintain said carriage 80 rigid to prevent tilting, yet permitting the carriage to have desired endwise movement in either direction along its tracks 81.

The carriage 80 at a desired point midway its ends and adjacent to a side margin thereof is provided with an upstanding bracket 140, with which is pivotally connected, as at 141, an end portion of a rod 142. This rod 142 is of desired length and has its opposite end portion operatively connected, as at 143, with the lower end portion of a hand lever 144. This lever 144 is

pivotedly mounted, as at 145, at a desired point intermediate its ends with a plate 146, herein disclosed as supported, as at 147, with an inner leg of one of the frames 108 and also, as at 148, by the upstanding post 149 carried by an adjacent sill 7. The upper margin of the plate 146 is formed to provide a rack 150 with which coacts a conventional latch mechanism 151 carried by the lever 144. Upon requisite swinging movement of the lever 144 the carriage 80 can be extended or retracted as desired within certain limits and held in selected position by the locking action between the latch mechanism 151 and the rack 150.

15 The auger 51 is shifted forwardly and rearwardly as desired within a certain range by proper turning of the turntable 79. To effect the desired turning of the turntable 79 the posts 71 of the side beams 78 have their upper portions connected by a cross member 152. Extending rearwardly from this member 152, at substantially the longitudinal center thereof, is an elongated shank 153 upon which threads a sleeve 154. 20 The outer end portion of this sleeve 154 is provided with a head 155 which carries a vertically disposed pivot member 156 with which is operatively connected an end portion of an elongated rod 157. This rod 157, as particularly illustrated in Figure 2, is disposed forwardly of the apparatus or device and is operatively connected, as at 158, with a hand lever 159 having its lower portion pivotally connected with an adjacent sill 7. This lever 159 carries a conventional latch mechanism 160 coacting with a rack 161 carried by said sill 7 whereby means are provided for locking the turntable in its selected turned adjustment.

When the auger 51 is raised said auger will assume by gravity its central position with respect to the rod 70 or arms 71 so that after said auger 51 has been adjusted forwardly and rearwardly and sidewise as may be required to bring the same over the desired spot for drilling, it is only necessary to lower the auger into contact 45 with the ground. It is to be particularly pointed out at this time that the proper positioning of the auger 51 can be readily effected after the structure has been brought into relatively close proximity to the spot by proper adjustment of the levers 144 and 159, and thus avoiding the necessity of having to spot the tractor exactly. It is also to be stated that the auger 51 is in rotation at all times when the sprocket wheel 25 is clutched to the shaft 27. It is believed 50 to be obvious that during a digging or drilling operation the brake band 116 is in release, as is also the clutch member 102.

From the foregoing it is thought to be obvious that a post hole digger constructed in accordance 55 with my invention is particularly well adapted for use by reason of the convenience and facility with which it may be assembled and operated.

I claim:

1. An earth boring apparatus comprising a 60 supporting structure, a carriage mounted on the structure for back and forth movement, a turntable mounted on the carriage, a boom carried by the turntable and extending upwardly and outwardly therefrom, an auger, means for supporting said auger by the boom for up and down movement, and means for rotating the auger.

2. An earth boring apparatus comprising a 65 supporting structure, a carriage mounted on the structure for back and forth movement, a turntable mounted on the carriage, a boom carried

70 75

by the turntable and extending upwardly and outwardly therefrom, an auger, means for supporting said auger by the boom for up and down movement, and means carried by the structure and coacting with the auger for rotating the auger in its different adjustments.

3. An earth boring apparatus comprising a supporting structure, a carriage mounted on the structure for back and forth movement, a turntable mounted on the carriage, a boom carried by the turntable and extending upwardly and outwardly therefrom, an auger, means for supporting said auger by the boom for up and down movement, means for rotating the auger, and means carried by the boom and operatively engaged with the auger for swinging the auger and maintaining the auger in selected swinging position.

4. An earth boring apparatus comprising a supporting structure, a carriage mounted thereon for back and forth movement, means for moving the carriage in either direction, a turntable mounted on the carriage, means for rotating the turntable, a boom carried by and extending upwardly and outwardly from the turntable, an auger suspended from the outer end portion of the boom and having free swinging movement in a general direction transversely of the boom, and means for rotating the auger.

5. An earth boring apparatus comprising a supporting structure, a carriage mounted thereon for back and forth movement, means for moving the carriage in either direction, a turntable mounted on the carriage, means for rotating the turntable, a boom carried by and extending upwardly and outwardly from the turntable, an auger suspended from the outer end portion of the boom and having free swinging movement in a general direction transversely of the boom, means for rotating the auger, said auger also having up and down movement independently of the boom, and means for raising the auger, said auger moving downwardly by gravity.

6. An earth boring apparatus comprising a supporting structure, a boom carried by said structure and extending upwardly and outwardly with respect to the structure, an elongated member rotatably engaged with the upper portion of the boom, a tubular member, means coacting with the tubular member and the elongated member for pivotally supporting the tubular member by the elongated member, a column freely disposed through the tubular member, said column and

tubular member being substantially vertically disposed, an auger connected to the lower portion of the column, means for rotating the auger, means for lifting the auger and column, and means for swinging the tubular member upon its pivot.

10 7. An earth boring apparatus comprising a supporting structure, a carriage mounted on the structure for back and forth movement, a turntable mounted on the carriage, a boom carried by the turntable and extending upwardly and outwardly therefrom, an auger, means for supporting said auger by the boom for up and down movement, means for rotating the auger, means for hitching the supporting structure to a tractor or the like, and ground engaging supporting members carried by said structure.

15 8. An earth boring apparatus comprising a supporting structure, a carriage mounted on the structure for back and forth movement, a turntable mounted on the carriage, a boom carried by the turntable and extending upwardly and outwardly therefrom, an auger, means for supporting said auger by the boom for up and down movement, means for rotating the auger, and releasable braking means for holding the auger in selected raised position, said auger moving downwardly by gravity upon release of said braking means.

20 9. An earth boring apparatus comprising a supporting structure, a carriage mounted on the structure for back and forth movement, a turntable mounted on the carriage, a boom carried by the turntable and extending upwardly and outwardly therefrom, an auger, means for supporting said auger by the boom for up and down movement, means for rotating the auger, and means for making inoperative the driving means for the auger upon abnormal resistance to the rotation of the auger.

25 10. An earth boring apparatus comprising a supporting structure, a carriage mounted thereon for back and forth movement, means for holding the carriage against tilting, means for moving the carriage in either direction, a turntable mounted on the carriage, a boom carried by the carriage, an auger suspended from the boom but free for up and down movement, means for rotating the auger, and means for lifting the auger, said auger moving downwardly by gravity.

JOHN W. HOUSTON.
